UNITED STATES PATENT OFFICE.

GEORGE R. WEST, OF WILKINSBURG, PENNSYLVANIA.

DESIGN FOR A PLATE.

SPECIFICATION forming part of Design No. 34,711, dated July 2, 1901.

Application filed June 1, 1901. Serial No. 62,813. Term of patent 3½ years.

To all whom it may concern:

Be it known that I, GEORGE R. WEST, a citizen of the United States, residing at Wilkinsburg, in the county of Allegheny and State of Pennsylvania, have invented and produced a new and original Design for a Plate, of which the following is a specification, reference being had to the accompanying drawing, forming a part thereof.

As shown in the drawing, the leading or material feature of my design is the shape or configuration of the border or edge of a plate or plaque, which consists of the representation of a number of owls 1, 2, and 3, perched upon a branch 4, and a rustic decoration 5. These two portions, the representation of the

owls and the rustic pattern, form the border of the plate or plaque, the center 6 being left plain.

It is apparent that this design is applicable 20 to plaques and other similar articles.

Having described my invention, what I claim as new, and desire to secure by Letters Patent, is—

The design for a plate, as herein shown and 25 described.

In testimony whereof I have hereunto set my hand.

GEORGE R. WEST.
